UNITED STATES PATENT OFFICE.

CHARLES E. SPEAKER, OF LOUISVILLE, KENTUCKY.

DESIGN FOR A COMBINED SEAT AND TELEPHONE-STAND.

49,319.

Specification for Design.

Patented July 4, 1916.

Application filed November 30, 1914. Serial No. 874,954. Term of patent 7 years.

To all whom it may concern:

Be it known that I, CHARLES E. SPEAKER, a citizen of the United States, and a resident of the city of Louisville, in the county of Jefferson and State of Kentucky, have invented a new, original, and ornamental Design for Combined Seats and Telephone-Stands, of which the following is a specification, reference being had to the accompanying drawing, forming part thereof.

In the drawing the figure is a perspective view of a combined seat and telephone stand, illustrating my new design.

I claim:

The ornamental design for a combined seat and telephone stand, as shown.

CHARLES E. SPEAKER.
